UNITED STATES PATENT OFFICE.

JOHN ELLIOT PEIRCE, OF DAYTON, OHIO.

DESIGN FOR A GROCERY-CABINET.

SPECIFICATION forming part of Design No. 23,117, dated March 13, 1894.

Application filed February 8, 1894. Serial No. 499,556. Term of patent 3½ years.

To all whom it may concern:

Be it known that I, JOHN ELLIOT PEIRCE, a citizen of the United States, residing at Dayton, in the county of Montgomery and State of Ohio, have invented and produced a new and original Design for Grocery Cases or Cabinets; and I do declare the following to be a full, clear, and exact description of the same, reference being had to the accompanying drawing, forming a part thereof.

The design herein shown and described relates to display cabinets or cases of the class especially adapted for displaying merchandise or other commodities in stores, &c.

The main features of the design are shown in the front elevation which shows the case to be of an oblong-rectangular form, and the front as consisting of a single horizontal panel with two horizontal rows of square panels set therein, one row above the other, the panels of one row differing from those of the other in dimensions.

The drawing annexed hereto shows in perspective, a cabinet constructed in accordance with my design.

The letter A indicates the body portion which is of an oblong-rectangular shape; the

front and rear horizontal panels vary in height, so that an end view of the cabinet will present an incline plane extending from the upper rear part to the upper front part of the cabinet. The panels B forming the ends are devoid of any ornamentation.

C designates a series of compartments with lids D, partitioned off in the upper horizontal portion of the cabinet. The front is constructed in a single horizontal panel E in which there are set two rows of rectangular panels.

F designates the upper horizontal row of these panels, and G denotes the lower horizontal row which are set in larger rectangular panels H. These rectangular panels arranged in double rows in the front of the cabinet impart a distinguishing feature thereto.

I claim—

The design for a display cabinet substantially as is herein shown and described.

In testimony whereof I affix my signature in presence of two witnesses.

JOHN ELLIOT PEIRCE.
